UNITED STATES PATENT OFFICE.

JOHN J. DUNLAP, OF COLUMBIA, SOUTH CAROLINA.

VALVE MECHANISM FOR ENGINES.

1,249,926.

Specification of Letters Patent. Patented Dec. 11, 1917.

Application filed June 25, 1915. Serial No. 36,337.

To all whom it may concern:

Be it known that I, JOHN J. DUNLAP, a citizen of the United States, residing at Columbia, in the county of Richland and State of South Carolina, have invented new and useful Improvements in Valve Mechanism for Engines, of which the following is a specification.

This invention relates to balanced valve mechanism for engines, being designed especially with reference to steam engines, the object in view being to provide accurate and reliable valve mechanism embodying a pair of rocking or oscillatory valves mounted in a steam or valve chest of novel construction, the valves being yoked together so as to operate simultaneously, one to admit and the other to exhaust the steam from the cylinder of the engine, means being provided for the proper lubrication of the rocking valves and also for adjusting the valves in relation to each other to produce the best results and obtain the highest efficiency of the engine.

With the above and other objects in view, the invention consists in the novel construction, combination and arrangement of parts, as herein described, illustrated and claimed.

In the accompanying drawings:

Figure 1 is a side elevation illustrating a portion of the cylinder of an engine, also showing the steam chest and valve operating means.

Fig. 2 is a longitudinal section through the same.

Fig. 3 is a cross section on the line 3—3 of Fig. 2.

Fig. 4 is a cross section on the line 4—4 of Fig. 2.

Fig. 5 is a plan view of the steam chest showing the valve operating mechanism.

The cylinder of the engine is designated at 1 in which operates the usual reciprocating piston 2, the cylinder being provided with the heads 3 and 4, 5 designating end casings which inclose the cylinder heads and the fastening means 6 by means of which the cylinder heads are secured to the body of the cylinder. The cylinder is shown as provided with the usual steam passages 7 and 8, the inlet chambers 9 and 10 and the exhaust chamber 11.

The steam or valve chest 12 in which the valves are mounted is provided with a series of internal webs 13 extending longitudinally thereof as best shown in Fig. 4 and

these webs are bored to provide openings 14 permitting bushings 15 to be inserted through the webs and supported thereby, the said bushings, two of which are employed, containing cylindrical valves 16 and 17 each having a generally cylindrical shape and each of said valves being formed with an inlet cavity 18 and an exhaust cavity 19, each of said cavities being substantially semi-cylindrical in cross section as shown in Fig. 2. Each of the bushings 15 is provided with ports 20, 21 and 22, the port 20 communicating with the inlet chamber 12, the port 21 being adapted to register with the steam passage 8 and the port 22 communicating with the exhaust chamber 11. In addition to the ports 20, 21 and 22 each bushing is provided with a plurality of lubricating holes or ports 23 to admit lubricating material to the outer surface of the valve, the lubricating material being admitted to the chest 12 through pipes 24. Relief valves 25 are shown arranged at opposite ends of the chest 12 to relieve vacuum in the steam cylinder and allow the engine to drift or run free when the steam is cut off therefrom.

The valves 16 and 17 are provided with stems or shafts 26 passing through stuffing boxes 27 in the opposite sides of the chest 12, the projecting ends of the shafts 26 having fast thereon arms 28 to which are pivotally connected at 29, the substantially parallel and opposite arms or branches 30 of a valve 90 operating yoke. Between the arms 28 of the valves, the branches of the yoke are made longitudinally extensible as illustrated in Fig. 1 wherein turn buckles 31 are employed for the purpose, the construction just referred to enabling the valves to be properly adjusted in relation to each other to obtain the highest efficiency of the engine.

In connection with each of the steam passages 7 and 8 and located between the valves 100 and the cylinder I employ cut-offs 32 in the form of slides which are insertible in and removable through slots 33 in the bottom of the steam chest, the outer ends of the slots 33 being closed by means of removable plates 105 or closures 34. In case one of the valves should for any reason become inoperative, the plate 34 adjacent thereto is removed and a cut-off 32 is inserted therein as illustrated in Fig. 2, after which the plate 34 is again placed in position to avoid any leakage of steam. The cut-off 32 does not, how-

ever, interfere with the remaining steam passage which therefore permits the piston to be driven in one direction by the expansion of the steam, the piston being returned 5 to the initial end of its stroke by the usual connections such as the piston rod and connecting rod of a locomotive or other engine.

From the foregoing description, taken in connection with the accompanying drawings, 10 it will now be understood that the valves 16 and 17 oscillate or rock simultaneously and equally in the same direction, said valves operating alternately as inlet and exhaust valves. The valves are adjustable in relation to each other by means of the longitudinally extensible yoke by which said valves are operated and the valves are lubricated through the holes or ports 23. The bushings or valve casings 15 are firmly supported in 15 place at various intervals by the webs 13 thereby making a strong and durable construction and enabling new bushings to be substituted for bushings that have become so worn as to admit of leakage of the steam. Furthermore, as stated, should one of the 20 valves become injured or rendered inoperative for any reason, said valve may be cut off from the cylinder by means of the slide or cut-off 32 thus enabling the engine as a 25

whole to continue in operation until an opportunity is presented to make the necessary 30 repairs.

What I claim is:—

In engine valve mechanism, the combination of an engine cylinder, a valve chest having internal webs in spaced parallel relation to each other bored to form parallel series of openings, hollow cylindrical bushings inserted through said openings, a pair of rocking valves mounted in said bushings for equal and simultaneous rocking movement on parallel axes, each of said valves being formed with a single inlet and a single exhaust cavity in the outer face thereof so arranged that the inlet cavity is adapted to 40 place the chest and one of the steam passages of the cylinder in communication and the exhaust cavity is adapted to place said steam passage of the cylinder in communication with the exhaust chamber, and means 45 located exteriorly of said chest for simultaneously rocking said valve.

In testimony whereof I affix my signature in presence of two witnesses.

JOHN J. DUNLAP.
